(57) **CLAIM**

The ornamental design for a squirrel baffle, as shown and described.

DESCRIPTION

FIG. 1 is a perspective view of a squirrel baffle showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view showing the squirrel baffle with its upper parts open;

FIG. 10 is an enlarged view of portion 10 in FIG. 1;

FIG. 11 is an enlarged view of portion 11 in FIG. 1;

FIG. 12 is an enlarged view of portion 12 in FIG. 2;

FIG. 13 is an enlarged view of portion 13 in FIG. 3;

FIG. 14 is an enlarged view of portion 14 in FIG. 8;

FIG. 15 is an enlarged view of portion 15 in FIG. 9;

FIG. 16 is a perspective view showing the squirrel baffle in an assembled state; and,

FIG. 17 is a perspective view showing the squirrel baffle in an alternate assembled state.

The evenly dashed broken lines illustrate features of the squirrel baffle and environmental subject matters that form no part of the claimed design; The unevenly dashed broken lines define the boundaries of the enlarged views and form no part of the claimed design.

1 Claim, 17 Drawing Sheets
